UNITED STATES PATENT OFFICE.

WALTER B. MANNY, OF ST. LOUIS, MISSOURI.

CIRCUIT-CLOSER.

SPECIFICATION forming part of Letters Patent No. 354,919, dated December 28, 1886.

Application filed July 3, 1886. Serial No. 207,027. (No model.)

To all whom it may concern:

Be it known that I, WALTER B. MANNY, a citizen of the United States, residing in the city of St. Louis, State of Missouri, have invented a certain new and useful Improvement 5 in Electric-Bell Door Knockers, of which the following is a full, clear, and exact description.

My invention relates to door-knockers, combined with means for ringing an electric bell, 10 and has for its object to enable a bell to be rung by the operation of the knocker, instead of separately, as heretofore.

On the accompanying drawings, Figure 1 is 15 a side sectional view of a door-knocker and its appurtenances constructed and arranged according to my invention; Fig. 2, a front sectional view, and Fig. 3 a front elevation, respectively, of the same, like letters of reference denoting like parts in all the figures.

20 *a* represents a door-knocker, which is swung or hinged in bearings *b*, carried by and projecting from the knocker-plate *c*, the latter being made of brass or other suitable metal, formed with the ornamental head *d*, and 25 screwed or otherwise fixed to the door *e* in the ordinary manner.

Above the knocker *a* is arranged a flat steel 30 or other metal spring, *f*, which projects from the inside of the ornamental head *d*, (or from some other convenient part of the plate *c*,) to 35 which it is secured, and insulated therefrom by a piece of vulcanized rubber or other suitable material, *g*. From the flat spring *f* an insulated wire, *i*, extends through the door *e* to a suitable battery for generating an electric 40 current, the other wire, *j*, of this battery being attached on the inside of the door *e* to the knocker-plate *c* by the bolt *k*, or otherwise, as found most convenient.

45 On the hinged portion of the knocker *a*, be-

tween its bearings *b* and immediately in front of the flat spring *f*, is an arm or lever, *h*, which normally, or when the knocker *a* is not in use and resting against the knocker-plate *c*, as shown in full lines, Fig. 1, is out of contact 45 with the flat spring *f*.

On lifting the knocker *a* from its plate *c* the arm or lever *h* will come in contact with and displace the flat spring *f* into the position shown by dotted lines in Fig. 1, and in so doing will close the circuit *i,j*, and ring an electric bell placed thereon. On bringing down the knocker *a* onto the plate *c* the arm or lever *h* is returned to its normal position, or out of contact with the flat spring *f*, and the circuit 55 *i,j* being thereby broken the bell will cease to ring, and the knocker *a* sound; or, in lieu of a flat spring, *f*, I may use any other suitable metal surface for insuring the proper contact therewith of the arm or lever *h*. 60

I am aware that it is not new to connect the knocker on the same circuit with an electrical bell in such manner that when the knocker is set in motion it also rings the bell, as is described in English Letters Patent No. 8,622, 65 of 1885, and I do not desire to claim the same, broadly.

I claim—

The door-knocker *a*, formed with an arm or lever, *h*, in combination with spring *f*, knocker-plate *c*, and wires *i,j* from an electric battery, substantially as shown, and for the purpose described. 70

In testimony whereof I affix my signature, in presence of two witnesses, this 29th day of June, 1886.

WALTER B. MANNY.

Witnesses:

S. L. SCHRADER,
PAUL BAKEWELL.
